UNITED STATES PATENT OFFICE.

IRVING R. LEDERER, OF PROVIDENCE, RHODE ISLAND, ASSIGNOR TO PROVIDENCE STOCK COMPANY, OF PROVIDENCE, RHODE ISLAND, A CORPORATION OF RHODE ISLAND.

METAL FABRIC.

Application filed January 30, 1924. Serial No. 689,537.

To all whom it may concern:

Be it known that I, IRVING R. LEDERER, a citizen of the United States, residing at Providence, in the county of Providence and State of Rhode Island, have invented certain new and useful Improvements in Metal Fabrics, of which the following is a specification.

This invention relates to an improved construction of metal fabric; and has for its object to provide a narrow metal fabric having a flexible body portion formed of intermeshing wire or strands and bordered by a flexible member which is attached to the margins of the fabric in such a way as to prevent its strands from raveling.

With these and other objects in view, the invention consists of certain novel features of construction, as will be more fully described, and particularly pointed out in the appended claims.

In the accompanying drawings:

Figure 1 is a face view representing one construction of fabric in which the strands are woven together with their ends secured to marginal links to hold them in proper position in the fabric;

Fig. 2 is a face view showing the fabric which is formed by intermeshing helical coils of wire, the ends of the coils being connected to a chain construction which forms the margins of the fabric;

Fig. 3 is a sectional edge view approximately on line 3—3 of Fig. 2; and

Fig. 4 is a detail showing a single helical coil, a plurality of which may be interlocked or interwoven to form the fabric.

It is found in the construction of narrow metal fabrics which are usually made of precious metal and more particularly adapted for use as bracelets, chains, belts and many other purposes, that unless their edges are formed with a selvage by bending the wires in some way to lock the strands from becoming disengaged from each other, that it is desirable to secure a strip or member along this unfastened edge to perform the function of a selvage; and to accomplish this in a simple and practical way which will not destroy the flexibility of the fabric, I have soldered to the marginal edges of the fabric the links of a metal chain which performs the desired function and at the same

time provides a fabric which is extremely handsome and attractive in appearance and serves many useful purposes; and the following is a detailed description of one construction of fabric by which these advantageous results may be accomplished:

With reference to the drawings, 10 designates the body of the fabric which in Fig. 1, is shown as being constructed by weaving strips or strands of wire 11 together. The ends 13 of these strands along the sides of the margins are soldered to the links of the chain 12 and thus the strands are locked in their respective positions in the fabric and prevented from being withdrawn therefrom. The chain links being, of course, flexible do not detrimentally affect the flexibility of the fabric.

In other instances the wire fabric is constructed by intermeshing or interweaving helical coils such as coils 14 shown in Fig. 4, to form a fabric such as that shown in Figs. 2 and 3, the coils of such a fabric having a tendency to work endways when the fabric is flexed if not locked in the fabric, and in order to lock these coils in the fabric without bending the ends of the coils, I have soldered a chain to the edges of the fabric, which effectually secures the coils in their proper positions therein and at the same time does not detrimentally affect the flexibility of the fabric.

This fabric when constructed of these coils must necessarily have a substantial thickness and in the attaching of the links of the chain to this fabric, I have preferably set these links at right angles to each other, as illustrated in Fig. 3, and attached the opposite edges of each adjacent link to the opposite edges of the fabric with respect to its thickness, which permits the use of a chain with links of a substantial width and which also permits the rolling down of the face of the fabric together with the chain attached thereto to form the desired finished surface on the face of the fabric.

The strands of these fabrics may be made of any of the precious metals, the combinations of the different colors of the precious metals rendering the fabric handsome and attractive in appearance; and the border formed by the chain performs the function of locking the strands in their proper posi-

tions and at the same time materially adds to the attractive and novel appearance of the fabric.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An article of manufacture comprising a flexible metallic fabric body, and a flexible edging formed of connected links, a portion of each link being permanently secured to a contiguous portion of the edge of the fabric body.
2. An article of manufacture comprising a flexible metallic fabric body, and a flexible edging formed of connected links, one edge

of each link being permanently secured to a contiguous portion of the edge of the fabric body.

3. An article of manufacture comprising a flexible metallic fabric body, and a flexible edging formed of connected links, said links being set at an angle to the plane of the fabric body, a portion of each link being permanently secured to a contiguous portion of the edge of the fabric body.

4. A metal fabric of substantial thickness having a body portion of intermeshing strands of wire, and a chain having its alternate links arranged substantially at right angles to each other in cross-section, said links being soldered alternately to the opposite edge portions of the fabric with respect to its thickness.

In testimony whereof I affix my sig- 40 nature.

IRVING R. LEDERER.
